UNITED STATES PATENT OFFICE.

JEREMIAH BINGHAM, OF TOLEDO, OHIO, ASSIGNOR TO THE TOLEDO MACHINE AND TOOL COMPANY, OF TOLEDO, OHIO, A CORPORATION OF OHIO.

RIVETING-MACHINE.

No. 850,615.

Specification of Letters Patent.

Patented April 16, 1907.

Application filed June 4, 1906. Serial No. 320,030.

To all whom it may concern:

Be it known that I, JEREMIAH BINGHAM, a citizen of the United States, and a resident of Toledo, in the county of Lucas and State of Ohio, have invented a certain new and useful Riveting-Machine; and I do hereby declare the following to be a full, clear, and exact description of the invention, such as will enable others skilled in the art to which it applies to make and use the same, reference being had to the accompanying drawings, and to the figures of reference marked thereon, which form a part of this specification.

My invention relates to means for riveting ears or handle-clips to pail-bodies, coal-hods, pans, tubs, metal boxes, or other work of a similar nature, and has for its primary object the provision of a simple and improved form of machine of the class which is adapted to both draw the rivets through the work and head them at a single operation.

The operation, construction, and arrangement of the parts of one form of the invention are fully described in the following specification and illustrated in the accompanying drawings, in which—

Figure 1 is a side elevation of a power-press equipped with my improved riveting attachment with a portion of the press-frame in section. Fig. 2 is an enlarged front elevation of the movable riveting part and horn in normal relative positions with a portion of the horn in section on the dotted line *x* in Fig. 3. Fig. 3 is a side elevation of Fig.

Fig. 4 is an enlarged cross-section taken on the dotted line *y* in Fig. 3 with the movable riveting part in lowered position. Fig. 5 is a central longitudinal vertical section of Fig. 4. Fig. 6 is a front view of the upper riveting part and horn in the position shown in Fig. 1, and Figs. 7 and 8 are a front elevation and cross-section of a portion of a pail or other article with ear attached.

Referring to the drawings, 1 indicates the frame, and 2 the slide or plunger, of a power-press of any suitable construction. Secured to the frame 1, as at 3, below the plane of movement of the plunger 2, is a horn 4, which is of suitable size and shape to carry the work being operated on and is faced on its upper side with a hardened metal plate 5. This horn is provided on its upper surface with the vertically-disposed transversely-

alinning fixed gage-pins 6 and 7 for gaging the relative positions of the pail or other article 55 8 and ear 9 as they are positioned on the horn 4 preparatory to being riveted together and is also provided with the yieldingly-mounted gage-pin 10, which has its upper end made conical in form to partially pass through the 60 bail-eye of the ear. This latter gage-pin is disposed centrally between the fixed pins 7 and slightly to the rear thereof, as shown in Figs. 2 and 3, and is carried by a pocket 11 in the horn, the lower portion of which is enlarged to receive the lower shouldered end of the pin and the coiled compression-spring 12, as shown in Fig. 5, the lower end of said pocket being closed by a plug 11^a. One or more shallow pockets 13 are formed in the 70 surface of the plate 5 to receive the lower headed ends of the rivets 14.

The movable riveting part of my invention is carried above the horn 4 by the press slide or plunger 2, and consists of the head 15, 75 which is attached to the lower end of the slide or plunger in a suitable manner and carries the relatively fixed rivet headers or sets 16 and the yielding pressure plate or foot 17. The rivet headers or sets 16 have their 80 upper ends removably secured, by means of set-screws 16^a, within suitable pockets formed in the under side of the head 15 and their lower ends slidingly mounted within apertures in the pressure-foot 17 in position to 85 coact with the rivets on the horn when lowered.

The pressure-foot 17 is shown as being of L-shape construction with its lower surface concave to conform to the contour of the horn 9c and also provided with a pocket, as shown at 18 in Fig. 5, for receiving the offset portion of the ear 9. The foot 17 is movably secured to the head 15 by the screws 19 and 20, the former of which pass through the slots 21 in 95 the vertical portion of the foot, while the latter has its lower end threaded to the horizontal portion of the foot and its upper end penetrating the head with its head mounted for vertical movement within the pocket 22 100 therein, as shown in Figs. 3 and 5. Encircling the screw 20 is a coiled compression-spring 23, which has its ends abutting the opposing surfaces of the head 15 and foot 17 and is adapted to maintain them in yielding 105 spaced relation, as shown in Figs. 2 and 3.

As it is necessary during a portion of the riveting operation that the foot 17 be maintained in rigid relation to its carrying-head, a pendent dog 24 is pivoted to each side of the head, as at 25, and provided intermediate its ends with a shoulder 26, which is adapted to coact with the contiguous upper side edge of the foot when in extended or normal position relative to its head, as shown in Fig. 2. The dogs 24 remain shouldered on the foot 17 until the rivets on the horn have been drawn or forced through the work on the downstroke of the plunger, at which point in their downward movement the ends thereof come in contact with the beveled ends of the alining spreader-plugs 27, which are carried within vertical pockets 28, provided in the sides of the horn 4, as shown in Fig. 2. An adjustment of these spreader-plugs is effected by means of the adjusting-screws 29, which are threaded through the bottoms of said pockets and retained in rigid adjusted position by lock-nuts 30, mounted thereon, as shown. A coiled contraction-spring 31 has its ends secured to the opposite dogs 24 to normally maintain them in contracted position. On the downstroke of the pressure-foot the gage-pins 6 and 7 on the horn 4 project within alining apertures provided in the foot, as shown by dotted lines in Fig. 2.

I wish it understood that I do not desire to be limited to the exact details of construction shown and described, for obvious modifications will occur to a person skilled in the art.

The operation of the invention is as follows: The rivets are first placed in the pockets provided therefor on the horn 4, the pail-body or other article 8 placed over the rivets with its rim abutting the outer gage-pins 6, after which the perforated ear 9 is placed upon the pail-body and located in proper position relative thereto due to its bail-eye being placed over the conical end of the movable gage-pin 10 and its sides abutting the two fixed gage-pins 7. The parts of the work being thus properly positioned on the horn, the press is put in operation, and on the downstroke of the pressure-foot 17 the rivets are drawn or forced through the metal of the body 8 and alining rivet-eyes of the ear 9, due to the dogs 24 shouldering on the opposite edges of the foot and maintaining it in rigid relation to its head. As soon as the rivets are forced through the work the lower ends of the dogs 24 strike the beveled ends of the spreader-plugs 27 and are forced outwardly thereby to effect a release of the pressure-foot. On the release of the dogs 24 the continued descent of the plunger causes the pressure-foot 17 to be compressed toward its carrying-head 15 against the tension of the spring 23 and the lower ends of the rivet

headers or sets to work through said foot and effect a heading of the upper ends of the rivets against the work. On the upstroke of the plunger the parts assume their normal positions with the pressure-foot extended and the dogs shouldered thereon in readiness for the next downstroke.

It is apparent with this construction of riveting attachment that the two operations—namely, the drawing and heading of the rivets—are completed at one stroke of the machine and without necessitating a change of position of the work, and that it can be used successfully for the drawing and heading of one or more rivets on small work—such, for instance, as the riveting of ears or handle-clips to pail-bodies, pans, tubs, metal boxes, or similar work.

Having thus described my invention, what I claim as new, and desire to secure by Letters Patent, is—

1. The combination with the reciprocatory head, attached rivet sets, and work-support in a riveting-machine, of an L-shaped pressure-foot yieldingly carried by the head and having a portion projecting thereunder and perforated to receive the rivet sets, said foot having its working face normally positioned in advance of the ends of the rivet sets, pendent members carried by the head and shouldered to normally lock with the foot to retain it in fixed position relative to the head, and means carried by the work-support for effecting a release of said members at a predetermined point in the movement of the foot.

2. In a riveting-machine, a work-support, a reciprocatory head, a rivet set fixed thereto, a pressure-foot yieldingly carried by the head and having a subjacent portion perforated to permit a working of the rivet set therethrough, pendent dogs pivoted to the head and normally shouldered intermediate their ends on the pressure-foot to retain it in fixed relation to the head, and means carried by the work-support for coöperating with the lower ends of the dogs at a predetermined point in their descent to effect a release of the pressure-foot.

3. In a riveting-machine, a work-support, a reciprocatory head, rivet sets fixed thereto, an L-shaped pressure member having its leg slotted and slidingly secured to the head and its foot projecting under the head and perforated to permit a working of the sets therethrough, springs interposed between the foot and head, dogs pivotally carried by the head and shouldered intermediate their ends to engage the sides of the foot and retain it in fixed relation to the head, means normally retaining the dogs shouldered on the foot, and means carried by the work-support to effect a release of the dogs at a predetermined point in their descent.

4. The combination with the rivet sets and work-support in a riveting-machine, of a yieldingly-mounted pressure-foot normally having its working face positioned in advance of the ends of the rivet sets, shouldered dogs normally locking with the pressure-foot to retain it in fixed position relative to the rivet sets and having extensions projecting below the pressure-foot, and means coacting with the extensions for effecting a release of the dogs at a predetermined point in the movement of the foot.
5. The combination with the work-support and coöperating riveting part in a riveting-machine, of fixed work-gages mounted on the

support and a gage-pin yieldingly mounted on the support and having a conical work-engaging end, substantially as described.

6. The combination with the work-support and coöperating riveting part in a riveting-machine, of fixed work-gages mounted on the support, and a gage-pin yieldingly carried by the support, substantially as described.

In testimony whereof I have hereunto signed my name to this specification in the presence of two subscribing witnesses.

JEREMIAH BINGHAM.
